WIRE FORMING AND CUTTING IMPLEMENT

Eugene Gawura, 6927 Coleman,
Dearborn, Mich. 48126

Filed Mar. 25, 1968, Ser. No. 11,124

Term of patent 14 years

U.S. Cl. D54—13
Int. Cl. D8—02

FIG. 1

FIG. 2

FIG. 4

FIG. 3

FIG. 5

FIGURE 1 is a side elevation view of a wire forming and cutting implement embodying my new design.

FIGURE 2 is a top plan view of the implement, taken on plane 2—2 in FIGURE 1.

FIGURE 3 is a side view of the head of the implement with the jaws closed.

FIGURE 4 is an enlarged section view, taken on plane 4—4 in FIGURE 1.

FIGURE 5 is an enlarged section view, taken on plane 5—5 in FIGURE 3.

I claim:

The ornamental design for a wire forming and cutting implement, as shown.
